(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first embodiment of a display screen or portion thereof with graphical user interface showing my new design;

FIG. 2 is a front view of a second embodiment of a display screen or portion thereof with graphical user interface showing my new design;

FIG. 3 is a front view of a third embodiment of a display screen or portion thereof with graphical user interface showing my new design;

FIG. 4 is a front view of a fourth embodiment of a display screen or portion thereof with graphical user interface showing my new design;

FIG. 5 is a front view of a fifth embodiment of a display screen or portion thereof with graphical user interface showing my new design;

FIG. 6 is a front view of a sixth embodiment of a display screen or portion thereof with graphical user interface showing my new design;

FIG. 7 is a front view of a seventh embodiment of a display screen or portion thereof with graphical user interface showing my new design; and,

FIG. 8 is a front view of an eighth embodiment of a display screen or portion thereof with graphical user interface showing my new design.

The outermost broken lines of uneven length show the display screen or portion thereof and form no part of the

(Continued)

claimed design. The other broken lines show portions of the graphical user interface that form no part of the claimed design.

1 Claim, 8 Drawing Sheets
